Inventor:

Robert Clark Russell

UNITED STATES PATENT OFFICE.

ROBERT CLARK RUSSELL, OF HILLMAN, MICHIGAN.

WASHBOARD.

SPECIFICATION forming part of Letters Patent No. 653,593, dated July 10, 1900.

Application filed August 15, 1899. Serial No. 727,345. (No model.)

To all whom it may concern:

Be it known that I, ROBERT CLARK RUSSELL, a subject of the Queen of Great Britain, residing at Hillman, in the county of Montmorency and State of Michigan, have invented a new and useful Improvement in Washboards, of which the following is a specification.

My invention relates to washboards, one object of the same being to provide means whereby the rubbing-strip of roughened or corrugated material may be adjusted on its support so as to present fresh surfaces when certain parts of the same become worn, and thereby lengthen the life of the board.

Other objects of the invention will herein-after appear.

The invention consists of a rubbing-strip in the form of an endless band, a sectional core on which said strip is adjustably secured, and a frame in which said rubbing-strip and core are removably mounted.

The invention also consists in certain features and details of construction and combinations of parts, which will be hereinafter more fully described and claimed.

In the drawings forming part of this specification, Figure 1 is a perspective view of the rubbing-strip employed. Fig. 2 is a similar view of the sectional core therefor. Fig. 3 is a perspective view of the washboard-frame with one of the sides thereof broken away and showing the core of the rubbing-strip seated therein in its normal operative position. Fig. 4 is a similar view of the washboard-frame with the rubbing-strip and its core at the lower end thereof in the position it assumes when being inserted into or removed from the frame.

Like reference-letters indicate like parts in the different views.

The side bars of the washboard-frame D are formed with longitudinally-extending grooves E on the inner sides thereof, which extend from a point adjacent to the upper ends of said side bars down to the extreme lower ends thereof. In these grooves when the parts of the washboard are assembled fit the side edges of a sectional core B, having grooves C along the upper and lower edges thereof. Surrounding the core B is a rubbing-strip A, which in the construction illus-

trated in the drawings is an endless band having a series of lateral corrugations thereon. The depressions formed by said corrugations 55 at the upper and lower edges of the strip A fit within the grooves C of the core B, and said strip is further secured to said core by means of removable pins F, extending through openings in the strip A and corresponding 60 openings G and H in the sectional core B. The core B, with its surrounding rubbing-strip A, is secured in position in the frame D by means of pins I and J, which extend through corresponding openings in said core. 65

It will be evident from the foregoing description that by removing the core B, with the rubbing-strip A thereon, from the washboard-frame D, which removal may be effected by withdrawing the pins I and J from their 70 seats and slipping said core and strip downwardly out of the grooves E, said core and strip may be reversed in position, so as to expose the opposite side of said strip from that which was formerly in use. This change 75 may be effected without any change in the relative positions of the core and strip. It frequently happens, however, that one part of the rubbing-strip of the washboard will become worn before another part and when 80 so worn the board is practically worthless and must be discarded. By my invention I provide means whereby different surfaces of the rubbing-strip A may be exposed, thereby lengthening the life of the board and increasing 85 the usefulness thereof. This change in surface is effected by first removing the core B and the strip A from the washboard-frame in the manner described and then pushing longitudinally one of the sections of the core 90 B out from the strip A. The said strip may then be turned on the remaining section of the core B until the worn part assumes a position at the rear of the board and fresh surfaces are exposed at the front of the board. 95 The section of the core B which has been removed may then be reapplied by inserting it into the endless strip A by a longitudinal movement the reverse of that which is necessary to remove said section. Unless some 100 means were provided for separating the two parts of the core B it would be impossible to shift the position of the strip A on said core, as two of the indentations in said strip are in

engagement with the grooves C at the opposite ends of said core. When the strip A has been reapplied to its core in the manner described, both these parts are reinserted into 5 the washboard-frame and secured in position by the pins I and J.

Having now described my invention, what I claim as new, and desire to secure by Letters Patent, is—

- 10 1. A washboard, comprising a frame, a rubbing-strip in the form of an endless band, a sectional core therefor, and means for adjusting the position of said strip on said core, as and for the purpose set forth.
- 15 2. A washboard, comprising a frame, a rubbing-strip in the form of an endless band having corrugations thereon, a core for said strip having grooves in its opposite ends in which

two of the indentations or depressions formed by said corrugations fit, and means for adjusting the position of said strip on said core, as and for the purpose set forth. 20

3. A washboard, comprising a frame having grooves in the side bars thereof, a rubbing-strip in the form of an endless band, a sectional core within said strip, the side edges of which fit within said grooves, means for adjusting the position of said strip on said core, and removable securing means for holding said core and strip in said frame, as and for 25 30 the purpose set forth.

ROBERT CLARK RUSSELL.
